UNITED STATES PATENT OFFICE.

MARION S. PARSONS, OF JOPLIN, MISSOURI.

POWER PUMPING HEAD.

Application filed June 7, 1922. Serial No. 566,627.

To all whom it may concern:

Be it known that I, MARION S. PARSONS, a citizen of the United States, residing at Joplin, in the county of Jasper and State of Missouri, have invented a new and useful Power Pumping Head, of which the following is a specification.

The device forming the subject matter of this application is a pump gearing, adapted 10 to be used in connection with pumps of that general type in which one piston rod moves upwardly, slowly, whilst the other piston rod moves downwardly, rapidly, and the invention aims to provide novel means 15 whereby there will be a lap in the movement of the piston rods that is, whereby each piston rod will move upwardly, at the time that the reverse in the movement of the other piston rod takes place, thereby avoiding all 20 jar and shock, the above mentioned result being brought about through the instrumentality of a simple combination of parts, and by a straight crank mechanism.

Although I have shown in the drawings, 25 one form which the invention may take, it will be understood that, within the scope of what is claimed, a mechanic may make alterations in the structure shown, without departing from the spirit of the invention.

30 In the drawings:-

Figure 1 shows, in elevation, a device constructed in accordance with the invention; Figure 2 is a top plan; Figure 3 is a front elevation wherein parts are broken away; 35 and Figures 4 to 9 are diagrams showing the relative positions of the parts, throughout the cycle of the operation.

The numeral 1 marks a frame, carrying any desired sort of operating mechanism, 40 such as a drive shaft 2 provided with pinions 3 meshing into gear wheels 4 on a shaft 5 journaled on the frame, the shaft having a crank whereunto a pitman 7 is pivoted as shown at 26, the pitman 7 being pivoted at 27 to one arm 8 of a bell crank lever 15 embodying an arm 9. Crank pins 10 are carried by the gear wheels 4 and are located in a straight line passing through the axis of the shaft 5 and the pivot point 26 between 45 the crank 6 and the pitman 7. The pitmans 11 are pivoted at 28 to arms 12 forming part of bell cranks 16 including arms 14. A rod or support 17, mounted on the frame 1, forms a fulcrum for the bell crank levers 15 and 16.

55 The numeral 18 marks a pump cylinder

and at 19 there is shown a vertical guide which may be mounted on the pump cylinder and on the frame 1. The upper ends of links 20 are pivoted at 30 to the arms 14 of 60 the bell crank levers 16 and are pivoted at their lower ends to a cross head 21, mounted to reciprocate on the guide 19 and connected to a hollow piston rod 22 mounted to reciprocate in the cylinder 18. A cross head 23 65 reciprocates on the guide 19 and carries a piston rod 24 which reciprocates in the piston rod 22. A link 25 is pivoted to the upper end of the rod 24 and is pivoted at 29 to the arm 9 of the bell crank lever 15. 70

The shaft 5 and the gear wheels 4 may be alluded to as a rotatable member, having crank elements 10 and 26 which are located 180 degrees apart, this portion of the device cooperating with other parts thereof, to 75 produce a lap in the movement of the piston rods.

When rotation is imparted to the drive shaft 2, the pinions 3 will impart rotation to the shaft 5 by way of the gear wheels 4, the 80 crank 6 will operate the bell crank lever 15 by way of the pitman 7, and the wrist pins 10 on the gear wheels 4, acting through the pitmans 11, will operate the bell crank levers 16, the bell crank levers 15 and 16 85 tilting on their fulcrum 17. From the arm 9 of the bell crank lever 15, motion will be transmitted to the piston rod 24 by way of the link 25, and from the arms 14 of the bell crank levers 16, motion will be transmitted 90 to the links 20 and to the piston rod 22. One rod moves upwardly at slow speed, to lift the liquid which is being pumped, whilst the other piston rod is moving downwardly. 95 The general construction of the device is such that there is a lap in the movement of the piston rods 24 and 22, that is, there is never a time when the liquid is not being lifted by one piston rod or the other, means being provided whereby there is a lap in the movement of each piston rod, at the time when the reversal in the direction of movement of the other piston rod takes place. The diagrammatic figures which are numbered 4 to 9 illustrate when and how the lap takes place, and point out, also, how the upward movement of the rod at slow speed, and the quick downward movement thereof are brought about.

The device forming the subject matter of 110 this application is a double lap-stroke pump, having two distinct bell crank movements,

these movements being produced without resorting to complicated devices of any kind. The bell cranks are operated from crank pins set 180 degrees apart, and motion is transmitted to each bell crank in such a way as to make it impossible for it to move, except in a changeable position, losing its center at the first movement of the actuating crank pin, and coming back to alinement with the crank pin once only, in every revolution. This movement takes place alternately, and the bell crank levers are operated in this manner, alternately.

The short arms of the bell crank levers, for instance, the arm 12 of the bell crank lever 16 never swings to the left (Figure 1) beyond a vertical plane passing through the fulcrum point 17. If the crank pin 10 and the arm 12 be considered, it will be obvious that if the arm 12 were three feet long, the point 28 would have a six foot throw provided that the said point moved through a full circle. In the device forming the subject matter of this application only so much of this circumference is used as results from the throw of the crank pin 10 and this throw of the crank pin 10 need not be more than eighteen inches. Only so much of a circumference described from the point 17 with a radius represented by the arm 12 is used, as produces, virtually, a straight line up and down movement in the piston rod. As a result, the lateral movement of the point 29, for instance, is very small and it is unnecessary to provide an extensive or elaborate cross head system. The variable speed resulting from the operation of the crank points 10 and 26 is neutralized, and each pump rod makes its down stroke at a speed which approaches uniformity, and makes its upstroke at a speed which approaches uniformity, the rod, however, moving downwardly, at a comparatively high speed, as distinguished from the relatively low speed at which the rod moves upwardly.

The structure shown and described is simple in construction and requires no fly wheels to carry the parts over center. Many objectionable cross head features common in other pumps have been eliminated. The upward stroke of the plunger rod is slow and even, the downward stroke being rapid. Any

stroke required may be secured, even between such wide limits as from six inches to twelve feet. The design of the device is such that it may be applied to pumps of any size and horse power, the general construction remaining unchanged, the alterations being made merely in the weight of the parts, to accommodate them to the duty which is to be performed.

It is to be observed that all of the stroke takes place above ground, although the stroke is long, no pit being necessary. A glance at Figure 1 will demonstrate the fact that there will be practically no difficulty in lining up the parts, when the pump is set up.

I claim:—

In a device of the class described, bell crank levers having a common fulcrum, the levers comprising long arms which extend in the same general horizontal direction from the fulcrum, and short arms which extend downwardly from the fulcrum, and means for causing the long arms to swing upwardly above and downwardly below a horizontal plane passing through the fulcrum, and for causing the short arms to swing through an arc which terminates at a vertical plane passing through the fulcrum, said means comprising crank elements having a common axis of rotation, and pitmans connecting the crank elements with the short arms of the bell crank levers, the points of connection between the pitmans and the crank elements being located in a straight line which is approximately at right angles to the short arm of one bell crank lever when said arm is in a vertical depending position, said points being below a horizontal plane passing through the connection between said short arm and its pitman when said short arm is in a vertical depending position, and means for connecting the long arms operatively with pump rods or the like.

In testimony that I claim the foregoing as my own, I have hereto affixed my signature in the presence of two witnesses.

MARION S. PARSONS.
